US00D350561S

United States Patent [19]

Hiraishi et al.

[11] Patent Number: Des. 350,561

[45] Date of Patent: ** Sep. 13, 1994

[54] **OFFSET PRINTING MACHINE**

[75] Inventors: **Etsuo Hiraishi, Tokyo; Hideo Aoyama; Katsushi Hirokawa**, both of Hiroshima, all of Japan

[73] Assignee: **Ryobi Ltd.**, Hiroshima, Japan

[**] Term: **14 Years**

[21] Appl. No.: **2,716**

[22] Filed: **Dec. 17, 1992**

[30] **Foreign Application Priority Data**

Jun. 19, 1992 [JP] Japan 4-18227

[52] U.S. Cl. **D18/53**

[58] Field of Search 101/136-137, 101/140-142, 145, 177, 183-185, 216-218, 232; **D18/53, 50**
